S. LAKE

APPARATUS FOR THE TREATMENT OF VARICOSE VEINS

Filed Sept. 5, 1924

Inventor:

Simon Lake
by M. N. Finekell Jr.

Attorney.

UNITED STATES PATENT OFFICE.

SIMON LAKE, OF MILFORD, CONNECTICUT.

APPARATUS FOR THE TREATMENT OF VARICOSE VEINS.

Application filed September 5, 1924. Serial No. 736,146.

Various methods and means have been devised for the treatment of varicose veins, the most successful of which include bandaging of the affected area. This bandaging, as ordinarily practiced, consists in applying a band, usually of elastic webbing, directly over the affected veins, and generally completely encircling the limb. A bandage of this type when worn for any appreciable 10 length of time becomes very irksome by reason of its constant pressure upon a restricted area and the consequent retardation of the circulation of blood throughout that area.

The object of my invention is to provide 15 an apparatus for the treatment of varicose veins, which, although contemplating the application of all necessary pressure to the area affected avoids the discomfort and irritation accompanying present practice.

20 The invention consists in an apparatus for treating varicose veins which permits the creation of pressure upon the entire affected area without direct contact of apparatus therewith, as I will proceed now to explain 25 and finally claim.

In the accompanying drawings illustrating 30 the invention, in the several figures of which like parts are similarly designated, Figure 1 shows, in dotted lines, a leg and foot with the apparatus of my invention applied thereto, the apparatus being shown in section. Fig. 2 is a fragmentary detail section of the upper portion of the apparatus upon a larger scale. Fig. 3 is a view similar 35 to Fig. 1 but showing modification.

The varix or enlargement of veins may be due to two causes, retardation of the flow of blood in the veins, or weakness of the walls of the veins at certain points; and in either 40 case the pressure of the blood is such as to distend the veins. This excess pressure of the blood in the veins may be counteracted to a degree by pressure applied externally to the affected area, and, as hereinbefore indicated, I propose to apply such pressure substantially evenly over the whole area, as distinguished from application of pressure to 45 restricted areas by bandaging in the manner now commonly employed.

50 To this end I provide, by my apparatus, for the substantially even distribution of equal pressure over an extended affected area by enclosing such area in a suitable cover-

ing or casing and introducing thereinto a compressed fluid, such as air. By confining 55 this compressed fluid within the casing the pressure of same may be raised to that point required to counteract or balance the pressure of the blood in the veins, thus permitting unrestricted natural flow of the 60 blood, and, in time, establishing normal conditions in the treated area.

In Fig. 1 I have shown a casing 1 of stocking shape and of such dimensions as to provide a space between it and the encased limb. 65 This casing is preferably formed of some non-elastic material such as cloth 2, impregnated or coated with rubber 3 so as to be fluid tight and impervious. The upper end of the casing is provided with an inturned 70 elastic band 4, preferably of pure rubber and capable of sufficiently closely and intimately embracing the limb to prevent escape of fluid under pressure introduced into the casing 1.

Arranged in the fold between the casing 1 and band 4 is a ring 5, preferably of rubber tubing, provided with openings 6 (Fig. 2) in its wall through which air or other fluid under pressure may be introduced into the casing, by means of a pump or compressor, such as an ordinary syringe bulb 7, connected by tubing 8 with the ring 5. A pressure relief or safety valve 9 of any ordinary type may be interposed in the pressure line to prevent the building up in the casing of undesired or unnecessarily high pressure. 85

It will be apparent that air forced under pressure from the bulb 7 into the casing 1 will be evenly distributed within the space between the casing and the limb enclosed thereby.

The band 4, as above described, closely embraces the limb, but its engagement therewith need not be so tight as to cause that irksome numbness caused by elastic bandages, stockings and the like, for the reason that the pressure established within the casing will have a tendency to force the band into pressure sealing contact with the limb. 95

In Fig. 3, I have shown a modification of 100 the apparatus in which separate casings 10 and 11 are provided for the upper and lower portions of the limb respectively, same being joined by a duct or tube 12 whereby pressure established in one casing will be 105 communicated to the other.

In this form of the apparatus, elastic bands 13, 14, 15 and 16 similar to, and operating in the same manner as the band 4, are provided at the upper and lower ends of the upper and lower casings 10 and 11 respectively.

The apparatus may be worn and the treatment practiced when the patient is confined to his bed, or is unable to move about, or it 10 may be worn under the clothing when the patient is able to go about his usual occupations, and in the latter case the bulb 7 may be concealed in some accessible portion of the clothing so that the pressure within 15 the casing may be maintained at the desired predetermined point.

Various modifications and changes may be made in the invention as above set forth without departing from its spirit or from 20 the scope of the following claims, and it should be so construed.

For example, it may be found expedient and beneficial to substitute for compressed air, as the fluid for filling the space between 25 the limb and casing, salt water or alum water, either of which would have a hardening effect upon the skin. Likewise, certain gases other than air and which would have a medicinal effect might be used.

Moreover, in treating wounds my apparatus might be found useful, not only as a bandage capable of applying a desired pressure to the wound without direct contact therewith, but as a means whereby the 30 wound might be medicinally treated or disinfected by the introduction within the casing of medicinal or disinfecting or other gases, such as oxygen and chlorine, or of 35

fluids or liquids having desired curative, disinfecting or medicinal properties.

What I claim is:—

1. An apparatus for treating varicose veins of a body member, comprising a casing fitted to but out of contact with said member and substantially conforming to the shape of said member, an elastic band carried by said casing and folded inwardly thereof and intimately embracing said body member, and means for introducing fluid under pressure into said casing including a ring lying between said casing and said band and provided with a plurality of openings for evenly distributing the fluid under pressure throughout said casing.

2. An apparatus for treating varicose veins of a body member, comprising a casing fitted to but out of contact with said member and substantially conforming to the shape of said member, an elastic band carried by said casing and folded inwardly thereof and intimately embracing said body member, and means for introducing fluid under pressure into said casing including a ring lying between said casing and said band and provided with a plurality of openings for evenly distributing the fluid under pressure throughout said casing and a pump capable of being concealed upon the person of the wearer for introducing fluid under pressure into said casing through said ring.

In testimony whereof I have hereunto set my hand this 4th day of September A. D. 1924.

SIMON LAKE.
